[57] CLAIM

The ornamental design for a fabric nap area for infants, as shown and described.

DESCRIPTION

FIG. 1 is a side and end perspective view of a fabric nap area for infants showing my new design;

FIG. 2 is a view of a first side of the fabric nap area of FIG. 1;

FIG. 3 is a view of a second side, opposite the first side, of the fabric nap area of FIG. 1;

FIG. 4 is view of a first end of the fabric nap area of FIG. 1;

FIG. 5 is a view of a second end, opposite the first end, of the fabric nap area of FIG. 1;

FIG. 6 is a view of the top of the fabric nap area of FIG. 1; and

FIG. 7 is a view of the bottom of the fabric nap area of FIG. 1.

FIG. 8 is a side and end perspective view of a first alternative embodiment embodiment to FIG. 1 of a fabric nap area for infants showing my new design;

FIG. 9 is a view of a first side of the fabric nap area of FIG. 8;

FIG. 10 is a view of a second side, opposite the first side, of the fabric nap area of FIG. 8;

FIG. 11 is view of a first end of the fabric nap area of FIG. 8;

FIG. 12 is a view of a second end, opposite the first end, of the fabric nap area of FIG. 8;

FIG. 13 is a view of the top of the fabric nap area of FIG. 8; and

FIG. 14 is a view of the bottom of the fabric nap area of FIG. 8.

FIG. 15 is a side and end perspective view of a second alternative embodiment to FIG. 1 of a fabric nap area for infants showing my new design;

FIG. 16 is a view of a first side of the fabric nap area of FIG. 15;

FIG. 17 is a view of a second side, opposite the first side, of the fabric nap area of FIG. 15;

FIG. 18 is view of a first end of the fabric nap area of FIG. 15;

FIG. 19 is a view of a second end, opposite the first end, of the fabric nap area of FIG. 15;

FIG. 20 is a view of the top of the fabric nap area of FIG. 15; and

FIG. 21 is a view of the bottom of the fabric nap area of FIG. 15.

FIG. 22 is a side and end perspective view of a third alternative embodiment to FIG. 1 of a fabric nap area for infants showing my new design;

FIG. 23 is a view of a first side of the fabric nap area of FIG. 22;

FIG. 24 is a view of a second side, opposite the first side, of the fabric nap area of FIG. 22;

FIG. 25 is view of a first end of the fabric nap area of FIG. 22;

FIG. 26 is a view of a second end, opposite the first end, of the fabric nap area of FIG. 22;

FIG. 27 is a view of the top of the fabric nap area of FIG. 22; and,

FIG. 28 is a view of the bottom of the fabric nap area of FIG. 22.
